(57) **CLAIM**

The ornamental design for a magnetic golf towel, as shown and described.

DESCRIPTION

FIG. 1 is a front perspective view of a magnetic golf towel, showing my new design;

FIG. 2 is an exploded front perspective view thereof;

FIG. 3 is an exploded front elevational view thereof;

FIG. 4 is an exploded rear elevational view thereof;

FIG. 5 is an exploded left-side elevational view thereof;

FIG. 6 is an exploded right-side elevational view thereof;

FIG. 7 is an exploded top plan view thereof; and,

FIG. 8 is an exploded bottom plan view thereof.

The broken lines in the figures depict portions of the magnetic golf towel that form no part of the claimed design. The remaining broken lines depict stitching, and do form part of the claimed design.

1 Claim, 4 Drawing Sheets
